UNITED STATES PATENT OFFICE.

WILLIAM DIEBEL, OF PHILADELPHIA, PENNSYLVANIA.

DESIGN FOR A PEDAL.

SPECIFICATION forming part of Design No. 32,232, dated February 13, 1900.

Application filed December 8, 1899, Serial No. 739,720. Term of patent 7 years.

To all whom it may concern:

Be it known that I, WILLIAM DIEBEL, a citizen of the United States of America, and a resident of the city and county of Philadelphia and State of Pennsylvania, have invented and produced a certain new and original Design for a Pedal, of which the following is a specification.

Figure 1 is a perspective view of a pedal, showing my new design. Fig. 2 is a plan view of the same, and Fig. 3 a cross-sectional view. As shown in the drawings, the leading or material feature of my design consists in the novel conformation of the pedal at the junction of the cylindrical bearing-ring *a* and the curved blade *b*, projecting at right angles therefrom, the latter being semicircular in

plan view where it joins the bearing-ring *a* and forming a central tangential union with the outer face thereof near its periphery and with a depending central projection on said periphery, and the circular outline of the ring *a* being preserved within the planes of the parallel sides of the blade.

What I claim is—

The design for a pedal substantially as shown and described.

Signed by me at Philadelphia, Pennsylvania, this 5th day of December, A. D. 1899.

WM. DIEBEL.
